UNITED STATES PATENT OFFICE.

ARTHUR C. FRIEDEL, OF SYRACUSE, NEW YORK, ASSIGNOR, BY MESNE ASSIGNMENTS,
TO WILLIAM W. VARNEY, OF BALTIMORE, MARYLAND.

OSCILLATOR.

Application filed September 4, 1926. Serial No. 133,557.

The object of my invention is the providing of an improved oscillator or acoustic vibrator.

A further object of my invention is the providing of an improved oscillator or acoustic 5 vibrator of the portable type provided with means of folding so that the same may be carried flat and formed into a curved position when in use.

A further object of my invention is the providing of an improved means of folding a 10 portable oscillator or acoustic vibrator whereby the portions near the folds may assume substantially the same curvature as other parts of the oscillator when in use.

15 A further object of my invention is the providing of an improved collapsible cone oscillator, having means of substantially forming the same into a cone and the securing thereof for use.

20 Oscillators or acoustic vibrators, the subject of this specification are especially adapted for "phonographic" and "loud speaker" uses and are equally well adapted for reception or reproduction. The means provided 25 for accomplishing the objects of this invention are equally applicable for forming what is known as a "megaphone" where portability may be had in flat form.

25 With the foregoing and other objects in view, my invention consists of the novel construction, combination and arrangement of parts as hereinafter specifically described and illustrated in the accompanying drawings wherein is shown the preferred embodiment 35 of my invention, but it is understood that changes, variations and modifications may be resorted to which come within the scope of the claims hereunto appended.

30 In the drawings of the herein described embodiment of my invention Figure 1 is a plan view of the oscillator unformed or opened out and in flat form, and ready to be curved and secured in position to form a cone; Figure 2 is a sectional view taken 45 through 2—2 of Figure 1, looking in the direction of the arrows and shows the fold formed by creasing one side, allowing the other side to be intact, to provide a tension when curved, thus curving its adjacent portions. Figure 3 50 is a view in elevation of the oscillator formed into the conical shape, ready for use. Figure 4 is a sectional view taken through 4—4 of Figure 3, looking in the direction of the arrows, and Fig. 5 is a view of my oscillator

folded flat for transportation and Fig. 6 is a 55 sectional view taken through 5—5 of Fig. 1.

Similar numerals refer to similar parts throughout the several views.

In this specification when I use the term "cone", I mean "conical" formed body, strictly speaking technically a truncated cone, but as it is so near a cone and when in use with its securing means of its operating mechanism is substantially a cone, consequently I term the formed body a cone. The cone or body "1" is 60 formed out of flexible material of any suitable character. I have found what is known in the trade as "cover stock", highly calendered suitable for this purpose.

"2" is a securing flap, preferably made of 70 the same material and glued or otherwise secured to cone or body "1" as shown in Figures 1 and 4. "3" is a securing means or as I might describe it a double eyelet, secured to body "1" and flap "2". A single eyelet attached to 75 either one of said members forming a knob will work, but I prefer the double eyelet, providing a slight space between members "1" and "2" for the insertion of the free edge "5" to body "1". "4" is a slot or slit in the periphery of "1" near its free edge "5". I have found that varnishing the vicinity of this slot "4" adds durability to this member. "6" and "7" are one-way folds or creases. These folds are made in the same direction from the center portion of member "1", the free edge folding under first, then the edge with the flap folding under next. This gives me a limit of fold when spread out in open or flat position, and when formed into the conical shape is 80 formed against these folds so as to give a continuous circular section within said cone, the folds being formed against the fold and in tension. When forming the cone after having unfolded body "1" into flat position forming 85 the cone against the folds as above suggested is continued until free edge "5" enters between flap "2" and body "1", said edge being slightly out of position along the element or cone having been slipped towards the center 90 to permit slot "4" to pass eyelet "3". When the two edges of the body "1" are substantially in contact, free edge "5" is slipped out and slot "4" is thus slipped around eyelet "3", substantially locking the periphery of the cone. The 95 cone is now formed and secured in operating position for attaching to a phonograph or other appliance upon which it is to work.

This is usually accomplished by a securing or clamping means at the apex of cone.

When the free edges of the cone are in contact and the slot "4" out in locked position around eyelet "3" the portion of the free edges between the center and securing flap "2" are prevented from being in contact, which if in contact might cause vibration or noise by touching, edge "5" is cut back 10 slightly as shown at "9", thus preventing contact at this portion of the free edges.

At the center an opening or hole "8" is provided, through which a bolt may penetrate for the securing means which forms no 15 part of this invention and is not further described.

Having thus described my invention, what I claim and desire to secure by Letters Patent is:

20 1. A collapsible conical sound reproducing diaphragm comprising an integral structure provided with a crease so as to fold in one direction only.

25 2. A folding conical sound reproducing diaphragm comprising a flexible surface

formed of a flexible material, one face of said material being provided with creases along certain lines of the exterior thereof to permit folding.

3. A collapsible conical sound reproducing diaphragm comprising a body provided with free edges along an element thereof and means for locking said free edges consisting of a slot in one of the edges and a knob in another edge in juxtaposition with said slot 35 and against which said slot engages.

4. A conical sound reproducing diaphragm, one edge of which is provided with a flap whereby the other edge may be engaged and means for securing said other edge 40 between said flap and a free edge.

5. A sound reproducing diaphragm, one edge of which is provided with a flap whereby the other edge may be engaged and means for securing said other edge between said flap and a free edge, and means for preventing contact in unsecured portions of the said free edges.

ARTHUR C. FRIEDEL.
